UNITED STATES PATENT OFFICE.

WALTER A. FRANTZ, OF CLEVELAND, OHIO.

WRINGER.

Application filed March 11, 1922. Serial No. 542,886.

To all whom it may concern:

Be it known that I, WALTER A. FRANTZ, a citizen of the United States, residing at Cleveland, in the county of Cuyahoga and 5 State of Ohio, have invented a certain new and useful Improvement in Wringers, of which the following is a full, clear, and exact description, reference being had to the accompanying drawings.

10 This invention relates to clothes wringers of the power operated type and has for its objects the provision of a new and improved means for mounting said wringer; the provision of a new and improved wringer-support; the provision of a wringer construction and wringer support so designed and assembled that two similar shafts can be used; while further objects and advantages 15 of the invention will become apparent as the description proceeds.

20

In the accompanying drawings I have shown one of the many physical forms in which my inventive idea can be embodied, although it will be understood that the same 25 is only illustrative and not limiting upon me. Fig. 1 is a side elevation of a wringer and its supporting and operating mechanism embodying my improvements; Fig. 2 is a detail view of one end of the wringer partly 30 in section; Fig. 3 is an end elevation of the wringer, the support being omitted; Fig. 4 is a horizontal section corresponding to the line 4—4 of Figs. 2 and 3; and Fig. 5 is a 35 view looking into the mouth of the gear casing, the retaining bolts being shown in place, but the wringer frame being removed.

Describing the parts by reference characters, 1 and 2 represent mating frame members having upright channeled end parts 3, 40 3 housing the bearing members 4, 4 in which are journaled the shafts 5, 5 of the rolls 6, 6. The frame members are also formed at one end with a second pair of registering channels 7 forming housings for the intermeshing gears 8, 8 with which the shafts are 45 provided. Any suitable means can be employed for producing, adjusting, and releasing the tension, the means here shown including a stirrup 10 mounted astride the upper bearing and having out turned feet 11 receiving the lower ends of springs 12 the upper ends of which are engaged by a yoke 13 bearing against the adjusting screw 14 which in turn is carried by a pivoted nut 15 held down by a releasable catch 16.

The support of this wringer comprises a

gear box 20, also preferably made in two mating halves joined on the vertical plane indicated at 21, and secured together by suitable bolts 22. This box has a depending 60 hollow pivot-portion 23 in which is journaled the drive shaft 24, and a horizontal, hollow receiving portion 25 in which is journaled the driven shaft 26. The end of this receiving portion has an elongated, vertically arranged mouth defined by the jaws 28, 28, and the end of the wringer frame has a pair of spaced jaws 29, 29 complementary thereto and arranged to engage the receiving portion in interfitting relation. In the 70 present embodiment the jaws 29 are located outside of the jaws 28, the two being complementarily ribbed and grooved to fit together and clamped rigidly by the bolts 30, 30.

75 The shafts 24 and 26 are connected together by suitable gearing as indicated in Fig. 1, and the shaft 26 is connected to the lower roll-shaft 5 by a suitable coupling 32, preferably of a type to permit a small degree of universal movement. For this purpose the roll shaft preferably projects a distance beyond the end of the wringer frame as shown; and the upper roll shaft is preferably made of equal length so as to 80 be interchangeable therewith, the box 25 being recessed to permit this as shown in Figs. 1, 2 and 5.

85 The construction herein illustrated produces an assembly of the maximum rigidity, 90 simplicity, compactness, and lightness. I do not, however, limit myself to the particular features of construction herein shown except as specifically recited in my claims.

Having thus described my invention what 95 I claim is:

1. In a power operated wringer, in combination, a frame, a pair of parallel roll-shafts journaled therein, a gear-box, a horizontally projecting hollow frame receiving portion 100 extending therefrom and having an elongated vertically extending mouth, a horizontal driven shaft journaled in said receiving portion, said frame and receiving portion having cooperating dove-tail provisions 105 for holding the same together, and means additional to such dove-tail provisions for holding one of said roll-shafts in alignment with said driven shaft.

110 2. In a power operated wringer, in combination, a frame having a pair of spaced uprights, substantially parallel jaws at one end

- defining an open mouth, a pair of parallel roll shafts journaled in said frame and having ends projecting through said mouth, a supporting bracket having an open mouth
- 5 adapted to register with said first mouth and having jaws complementary to said first jaws, an operating shaft journaled in said bracket, means for coupling said operating shaft to one of said roll-shafts, and means
- 10 for clamping said jaws together, said mouths being of sufficient vertical extent to permit the necessary vertical movement of the other roll-shaft.
3. In a power operated wringer, in combination, a frame having jaws and a supporting member having jaws complementary thereto, rolls journaled in said frame, driving mechanism in said supporting member, one set of said jaws being arranged to
- 15 open and close at right angles to the rolls, and means for clamping said last set of jaws upon the other set of jaws.
4. In a power operated wringer, in combination, a pair of mating frame members
- 20 which meet upon a vertical plane, each of said members having at one end a vertical jaw, said jaws defining a mouth, a hollow supporting bracket having a pair of jaws adapted to fit between said first jaws, a roll
- 25 shaft journaled in said frame and projecting
- through said mouth into said bracket, and transverse bolts clamping said jaws together.
5. In a power operated wringer, in combination, a pair of mating frame members which meet upon a vertical plane, each of said members having at one end a vertical jaw, said jaws defining a mouth, a second pair of hollow mating members which meet upon a vertical plane to form a gear box, one side of said gear box having a hollow supporting bracket terminating in spaced jaws complementary to said first jaws, roll shafts journaled in said frame, gearing in said gear box, operative connections between said gearing and one of said roll shafts, means securing together independently the mating members of said frame and gear box, and means clamping said jaws together in interfitting relation.
6. In a wringer, in combination, a frame, a pair of parallel roll-shafts journaled therein, a bracket for supporting said frame, and having a vertically faced receiving portion adapted to engage an end member of said frame, said frame and said receiving portion having interfitting dove-tail provisions whereby they are held together.

In testimony whereof, I hereunto affix my signature.

WALTER A. FRANTZ.
